No. 802,577.

PATENTED OCT. 24, 1905.

R. W. LYLE,
CONDUIT FOR ELECTRIC WIRES.
APPLICATION FILED FEB. 10, 1903.

UNITED STATES PATENT OFFICE.

ROBERT W. LYLE, OF NEW YORK, N. Y.

CONDUIT FOR ELECTRIC WIRES.

No. 802,577.

Specification of Letters Patent.

Patented Oct. 24, 1905.

Application filed February 10, 1903. Serial No. 142,702.

To all whom it may concern:

Be it known that I, ROBERT W. LYLE, a citizen of the United States, and a resident of New York, in the county and State of New York, have invented certain new and useful Improvements in Conduits for Electric Wires, of which the following is a specification.

My present invention pertains to conduits for electric wires, and more especially to such as comprise a plurality of sections; and the object of my invention is to provide sections such as are used in the construction of said conduits and which will be of such a form that they can be easily and cheaply manufactured, while embodying within said form means which are engageable by suitable members which are herein termed "dowels" and which when so engaged by the sections will secure the sections in alinement one with another, both longitudinally and transversely.

Conduit-sections have been made hitherto in which means for the purpose before referred to were provided. In these, said means were similar to those pertaining to my invention to the extent that they comprised grooves which were in some instances undercut, said grooves being in some instances formed in the external faces of the conduit-sections and longitudinally of the latter. In some instances the grooves extended from end to end of the sections, while in other instances the grooves extended a certain distance from each end and toward the center of each section, but were interrupted centrally of the sections. In the last-named form the end wall of each groove served as a stop to prevent excessive longitudinal movement of a dowel placed in the groove for the purpose hereinbefore related. It is desirable that a stop which is attached to a conduit-section should be provided for the purpose related, as thereby is obviated the necessity for providing a stop separate from the conduit-section which involves additional labor in its use. In the absence of such attached stops dowels were generally used of such length that their ends abutted one against another in the grooves in which they were located, one dowel thus acting as a stop for another. In practice it is found that conduit-sections which are made of the materials which are commonly used for the purpose may be more easily and cheaply made with the before-mentioned grooves extending from end to end of said sections than with the shorter

or interrupted grooves, and the form of conduit-section which embodies my invention is such that this desired end may be attained in combination with the provision of dowel-stops which are firmly attached to and are practically a part of each conduit-section.

In the drawings, Figure 1 is a side elevation of a conduit-section which embodies my invention, a dowel being shown in broken lines in position in said section. Fig. 2 is an end elevation thereof, a dowel also being shown in a groove. Fig. 3 is a partial central vertical longitudinal section thereof, two forms of stops and a dowel being shown therein; and Fig. 4 is a vertical transverse section thereof through the line *a a*, Fig. 1. Figs. 5 and 6 are detail sectional views illustrating one method of forming the stop in the longitudinal grooves.

Corresponding parts in all the figures are denoted by the same reference characters.

Referring to the drawings, *A* in a general way designates a conduit-section in which are formed grooves *a a*, which extend from end to end of the section *A* and are preferably undercut, as shown, and adapted to receive dowels, such as the member *b*, which is shown in broken lines in Fig. 1 and in full lines in Figs. 2 and 3. Dowel-stops *c c'* may be fixed in the grooves *a a*, in which said dowel-stops are firmly attached to the conduit-section. The dowel-stops may be of any convenient or desired form and of suitable dimensions. I prefer, however, to form them either, as at *c*, by impressing into the grooves *a a* in the green-molded conduit-section *A* a suitable device which will carry into said grooves a portion of the material of the outer parts of the walls of said grooves and firmly press said portion of material into said grooves *a a*, so that it becomes and remains integral with the conduit-section *A*, or by forming them, as at *c'*, by inserting into the grooves *a a* a portion of separate material which shall be either homogeneous with the material of the conduit-section *A* or of such a nature or form as to become and be firmly attached to said conduit-section, the attachment being effected either by the cementation of the stop to the section or in any other suitable manner. For the stops *c'* I prefer, however, to use cement which will adhere to and fix itself firmly within the grooves *a a*. Preferably the grooves *a a* are formed in the exterior faces

d d of the conduit-sections and on the median longitudinal lines thereof.

The uses and advantages of my invention will be readily understood and appreciated by those skilled in the art to which it appertains. As a conduit is being laid, by properly positioning sections A suitable dowels are placed in the grooves *a a* and serve to aline the sections one with another both longitudinally and transversely of the conduit, as the dowels so placed in a longitudinal plane across the joint between the conduit-sections serve to prevent movement of said sections either lengthwise or longitudinally or sideways or transversely. Relatively short dowels should be used, and the stops *c* or *c'* will prevent said dowels from moving longitudinally, the latter being thus retained in their normal positions—namely, partly in one section and partly in an adjacent and contacting section. It will be noted that suitable dowels will be retained in the grooves *a a* by reason of the undercut form of said grooves. It will also be noted that each groove *a* is divided by the dowel-stops into three longitudinal parts—one inner part *a'* and two outer parts *a'' a''*—and that the dowels lie in the outer parts *a''* only. It is obvious, however, that the inner part *a'* of a priorly-formed groove *a* may be completely filled, at least longitudinally, by the dowel-stops *c* or *c'*. This latter construction is not herein specifically shown and described, as it is concerned in the subject-matter of another application for patent concurrent herewith; but for the purposes of the present application the outer end faces of the dowel-stops are referred to by the term "dowel-stops" without reference to the extent or dimensions of said dowel-stops in a longitudinal plane with respect to the conduit-section.

In the case of conduit-sections which have more than four ducts—for instance, six or eight ducts—the longitudinal grooves on the exterior faces would instead of being formed on a median line of each of the faces be formed on the median line of the respective webs or partitions which form the plurality of ducts and on said median lines on all faces of the conduit-section. In the case of a four-way conduit-section, such as that herein illustrated, the median line of the webs or partitions is the median line of the conduit itself; but in the case of a conduit-section having a plurality of ducts greater than four in number the median line of the webs or partitions would of course not be the median line of the conduit-section itself. Hence in the latter instance the median arrangement of the longitudinal exterior grooves would be as above stated.

Under some circumstances when the stop or wall in the longitudinal groove, which divides said groove into a short end section for the dowel-pin, does not form a complete wall, entirely closing up the groove, moisture might

pass from the middle portion of the longitudinal groove, past the stop, between the dowel-pin and walls of the groove, between the abutting ends of the conduit-sections, and into the ducts. When it is desired to obviate this possibility, I prefer to make the stops in the longitudinal groove as a complete wall or cross-partition which will entirely close the groove and prevent any possibility of the passage of moisture into the end section of the groove which is provided for the dowel-pin. Such a completely-closed construction is shown in Fig. 5, the stop being in this instance formed by simply "pinching up" the material of the sides of the longitudinal groove to form a wall or partition, as at *c''*, extending entirely across the groove and completely closing the end of the dowel-pin portion from the middle open part of the longitudinal groove. I reserve the right to form this complete stop or closure in any other suitable or adapted manner for the purposes stated.

I do not desire to be understood as limiting myself to the details of construction and arrangement as herein described and illustrated, as it is manifest that variations and modifications may be made in the features of construction and arrangement in the adaptation of the device to various conditions of use without departing from the spirit and scope of my invention and improvements. I therefore reserve the right to all such variation and modification as properly fall within the scope of my invention and the terms of the following claims.

Having thus described my invention, I claim and desire to secure by Letters Patent—

1. A conduit-section for electric wires, and comprising longitudinally-grooved walls, and dowel-stops fixed in the grooves in said walls.
2. A conduit-section for electric wires, and comprising longitudinally-grooved exterior walls, and dowel-stops fixed in the grooves in said walls.
3. A conduit-section for electric wires, and comprising longitudinally-grooved walls, and dowel-stops fixed in the grooves in said walls and integrally of the conduit-section.
4. A conduit-section for electric wires, and comprising longitudinally-grooved exterior walls and dowel-stops fixed in the grooves in said walls and integrally of the conduit-section.
5. A conduit-section for electric wires, and comprising longitudinally-grooved walls, and dowel-stops consisting of suitably-formed portions of the walls of the grooves and fixed in the grooves in said walls.
6. A conduit-section for electric wires, and comprising longitudinally-grooved exterior walls, and dowel-stops consisting of suitably-formed portions of the walls of the grooves and fixed in the grooves in said walls.
7. A conduit-section for electric wires, and comprising longitudinally-grooved walls, and dowel-stops consisting of suitably-formed por-

- comprising walls grooved and undercut from end to end, and dowel-stops fixed in the grooves in said walls.
34. A conduit-section for electric wires, and comprising exterior walls grooved and undercut from end to end, and dowel-stops fixed in the grooves in said walls.
35. A conduit-section for electric wires, and comprising walls grooved and undercut from end to end, and dowel-stops fixed in the grooves in said walls and integrally of the conduit-section.
36. A conduit-section for electric wires, and comprising exterior walls grooved and undercut from end to end, and dowel-stops in the grooves in said walls and integrally of the conduit-section.
37. A conduit-section for electric wires and comprising walls grooved and undercut from end to end; and the dowel-stops consisting of suitably-formed portions of the walls of the grooves and fixed in the grooves in said walls.
38. A conduit-section for electric wires and comprising exterior walls grooved and undercut from end to end; and dowel-stops consisting of suitably-formed portions of the walls of the grooves and fixed in the grooves in said walls.
39. A conduit-section for electric wires, and comprising walls grooved and undercut from end to end; and dowel-stops consisting of suitably-formed portions of the walls of the grooves and fixed in the grooves in said walls and integrally of the conduit-section.
40. A conduit-section for electric wires and comprising exterior walls grooved and undercut from end to end; and dowel-stops consisting of suitably-formed portions of the walls of the grooves and fixed in the grooves in said walls and integrally of the conduit-section.
41. A conduit-section for electric wires, and comprising walls grooved and undercut from end to end on their median lines; and dowel-stops fixed in the grooves in said walls.
42. A conduit-section for electric wires, and comprising exterior walls grooved and undercut from end to end on their median lines, and dowel-stops fixed in the grooves in said walls.
43. A conduit-section for electric wires, and comprising walls grooved and undercut from end to end on their median lines, and dowel-stops fixed in the grooves in said walls and integrally of the conduit-section.
44. A conduit-section for electric wires, and comprising exterior walls grooved and undercut from end to end on their median lines; and dowel-stops in the grooves in said walls and integrally of the conduit-section.
45. A conduit-section for electric wires and comprising walls grooved and undercut from end to end on their median lines, and dowel-stops consisting of suitably-formed portions of the walls of the grooves and fixed in the grooves in said walls.
46. A conduit-section for electric wires and comprising exterior walls grooved and undercut from end to end on their median lines; and dowel-stops consisting of suitably-formed portions of the walls of the grooves and fixed in the grooves in said walls.
47. A conduit-section for electric wires, and comprising walls grooved and undercut from end to end on their median lines; and dowel-stops consisting of suitably-formed portions of the walls of the grooves and fixed in the grooves in said walls and integrally of the conduit-section.
48. A conduit-section for electric wires and comprising exterior walls grooved and undercut from end to end on their median lines; and dowel-stops consisting of suitably-formed portions of the walls of the grooves and fixed in said walls and integrally of the conduit-section.
49. A conduit-section having a longitudinal exterior groove extending from end to end, said groove being provided with a stop dividing the main portion of the groove from a short end portion adapted to receive a dowel-pin, said stop entirely closing the short end portion of the groove from the main portion, for the purpose set forth.
50. A conduit-section comprising a body portion formed with a pin-receiving opening restricted by material pressed from said body portion into the same.
51. A conduit-section comprising a body portion formed with a pin-receiving opening extending throughout the length thereof, said opening being restricted at a plurality of points by material pressed from the body portion into the same.
52. A conduit-section comprising a body portion formed with an undercut groove, and material of the body portion pressed into said groove for restricting the same.
